AUTOMATIC MIXTURE REGULATING DEVICE FOR INTERNAL-COMBUSTION ENGINES

Raymond de Filippis, New York, N. Y.

Application August 1, 1942, Serial No. 453,296

4 Claims. (Cl. 123—124)

1

This invention relates to improvements in automatic mixture regulating devices for internal combustion engines.

One of the objects of my invention is to provide simple and efficient means for automatically controlling and progressively varying the mixture being fed to the cylinders of an internal combustion engine in accordance with and in the ratio of the speed of the engine.

Another object of my invention is, in a device of the character described, to utilize as the operating and controlling element a slide valve movable in an air-admission conduit and preferably actuated by a rotatable propeller or fan, and to utilize as the actuating medium the air-stream at the varying velocities thereof in relation to the car at varying speeds of said car to actuate said propeller or fan.

Another object of my invention is, in a device of the character specified, to provide in connection with a valve and air-admission conduit of the character described, apertures for progressively increasing the supply of air in accordance with the increasing movement of the propeller blade and of the vehicle.

Still another object of my invention is, in an air regulating and controlling valve of the type specified, to utilize an air-admission conduit and to provide therein a slide valve adapted upon longitudinal movement in the conduit to progressively open a plurality of longitudinally-arranged apertures in accordance with the movement of the slide valve in combination with means for moving said slide valve in proportionate ratio to the speed of the vehicle.

Still another object of my invention is, in a slide valve of the character described, to provide air-intake apertures in the air-admission conduit and to progressively increase the size or area of such apertures from the bottom to the top of the path of movement of said valve.

Still another object of my invention is to utilize a propeller revolvable by a current of air as the progressive valve-moving and aperture-opening means and gravity plus normal suction through the conduit as the valve-closing means.

Another object of my invention is to position my slide valve and its air-admitting conduit on the intake manifold in the air stream of the conventional radiator fan and thus to procure automatic increase or decrease of the air supply in accordance with the speed of the engine and without modifying or affecting the adjustment of the mixture in the carburetor.

Another object of my invention is to provide,

2

in a device of the character described, means that will remain inoperative and ineffective at low speeds; for example, at speeds of less than 10 miles per hour; and will at higher speeds feed progressively increasing quantities of air through the intake manifold to the combustible mixture passing through said manifold, and thus will save gas at such higher speeds.

Another object of my invention is to provide an air-intake means that will cause agitation of the air during the intake of the same through my intake conduit and will thus cause such agitated air to be more readily mixable with the combustible mixture passing through the manifold.

Still another object of my invention is to utilize, in a device of the character specified, a slide valve and conduit by which a plurality of streams of air are admitted simultaneously and the volume of such streams are progressively increased in accordance with the movement of the valve and the speed of the vehicle.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawing, in which—

Fig. 1 is a view in side elevation of an engine showing my automatic mixture-regulating device mounted in position on the intake manifold.

Fig. 2 is an enlarged view showing in section a fragment of the intake manifold wall with my air regulator mounted therein.

Fig. 3 is a section on the line 3—3 of Fig. 2 looking in the direction of the arrows.

Fig. 4 is a view of my automatic mixture regulating device in side elevation and enlarged over the illustration thereof in Fig. 1.

My automatic mixture regulating device embodies two novel features, one comprising the use of a conduit or elongated casing provided with apertures and preferably a plurality of series of apertures that preferably increase in area or size from the inner to the outer end thereof together with a slide valve and actuating means therefor adapted to progressively open and close such apertures in accordance with and in proportionate ratio to the speed of the car, and the other is the use of a rotatable propeller movable

by an air-stream and preferably by the air-

stream of the radiator fan for progressively opening an air-admission aperture or apertures to the intake manifold and preferably moving a slide valve within an air-admission conduit of the type hereinabove specified.

Referring now to the drawing which illustrates a preferred embodiment of my invention, 10 indicates the engine as a whole which may be of any conventional type and as shown, is provided with an intake manifold 11 having a head 11a, on the side wall of which is mounted my air-regulating device 12, as more particularly illustrated in Figs. 1 and 2. The side-wall 11b of the head 11a is bored and tapped at 13, and I mount in this tapped bore an outwardly-projecting screw-threaded nipple 14, at the outer end of which I mount my said air-regulating device 12. My said air-regulating device, as shown, embodies an L-conduit 15 mounted on the nipple 14 and a straight tubular-conduit 16 threaded at one end into said L 15. The conduit 16 preferably has mounted therein a slide valve 17 adapted upon movement longitudinally or axially through the tubular conduit 16 to admit air through the L 15 and nipple 14 to the manifold 11. The valve member 17 is movable by the rotatable propeller 18 which as shown is mounted on a rod 19 connected with the sliding valve-member 17. The rod 19 is guided at its outer end in the bore 20' of cap 20 and in the preferred embodiment of my invention the valve member 17 fits loosely within the bore 21 of the tubular member 16 and has at one end a bevelled edge 22 adapted to seat upon the valve seat 23 and to close a main valve opening 23'. The body of the air-conduit or casing 16 is provided with a plurality of series of apertures 24 and 24'.

My slide valve casing is preferably positioned in inclined position on the manifold so that it will normally close by gravity. The threaded connections at 14, 15 permit some angular movement so that the angle of the casing can be adjusted.

The valve member 17 preferably fits loosely within the bore of the conduit casing 16 so as to admit a slight amount of air upon unseating from the valve seat 23 through the main valve opening 23'. So soon, however, as the valve member 17 is moved outwardly air is admitted through the inner members of the series of apertures 24 and 24', and as said valve member 17 is moved further outwardly additional air will be admitted through additional apertures of said series until the entire plural series of apertures 24 and 24' will be admitting air to the air-intake conduit or casing and through that conduit or casing to the manifold.

In preferred form of my invention illustrated, the plural series of apertures 24, 24' are arranged in pairs and these pairs are progressively increased in size or area in accordance with their position in relation to the outer end of the air-intake casing or conduit. When the speed of the vehicle is increased, it is obvious that a stronger current of air will be projected against the propeller 18 to move the valve member 17 outwardly in opposition to suction from the manifold which will, through the air conduit 16, retain said suction in relatively confined condition and will thus enable a constant pull to be maintained on the valve 17. Such constant pull of the suction will be overcome by the propeller pull which is progressively increased and strengthened in accordance with and in proportion to the speed of the vehicle.

Rotation of the propeller 18 renders the device 12 highly sensitive to the blast of air from the motor fan by reducing frictional resistance to sliding motion of the valve 17 and rod 19. Since these parts are caused to rotate, there is a combination of torsional and longitudinal forces which tend to quickly dislodge or loosen any dust particles which may enter the bearing 20 or which may be fine enough to seep through the filter hereinafter described. Since the parts 17, 18 and 19 are intermittently in rapid rotation while the automobile is being driven, the dust particles do not have an opportunity to settle and pack. Thus sensitivity to the blast of the fan is maintained in a high degree. Important as this is, the propeller 18 has a further advantage in that its blades offer a response to the air blast from the motor fan which is relatively uniformly proportioned to the force of that blast and hence to the speed of the motor. Such uniformity is due to the fact that the propeller blades do not offer an obstacle of excessive area at the region of the propeller; the angle of the blades affords a partial stream line effect; and finally, excessive eddy currents are avoided which cause a blast of air to transmit an uncertain and erratic force to the opposing surface.

In the embodiment of my invention illustrated, suitable protecting means is provided to protect and prevent clogging of dirt in the air-intake apertures 24 and 24', and in said preferred embodiment of my invention, I provide a protective casing 25 which, as shown, is mounted on spiders 26 and 26' and is provided at opposite ends with the screens 27 and 27', said casing 25 being, of course, open at its opposite ends to permit air to pass through said screens 27 and 27', and into the intake openings 24 and 24'.

The operation of the invention will now be briefly described. When the automobile is running at a low speed, which may be up to ten miles per hour, the valve portion 22 engages the seat 23 to close the latter so that the combustible mixture for the motor is as determined by the carburetor. This closing action is caused by gravity and suction overcoming the pull of the propeller 18. As the speed increases the valve 17 may move to the position shown in Fig. 2, in which the valve seat 23 is open, and some air leaks through the clearance between the side walls of the valve and of the tube 16. This is desirable because the carburetor is generally adjusted for a rich mixture, that is, one in which there is a considerable excess of fuel. As the speed further increases and becomes substantial, the proportioning of fuel to air by the carburetor changes so that the mixture becomes richer, because the coefficients of flow vary with the velocity of the gases in the carburetor, and for other reasons. The suction, however, diminishes as is well known in the art. Hence the valve 17 is moved by the propeller 18 to open the inlets 24, 24' progressively, as the motor speed increased. Thus additional air is supplied to the motor in approximate proportion to the increasing richness of the mixture as it leaves the carburetor, whereby the unburnt gases discharged from the motor are at a relative minimum. This additional air is supplied to the combustible mixture in a turbulent condition so as to instantly become a relatively homogeneous component of the combustible mixture. This is due to the fact that the air enters the tube 16 through opposed openings 24, 24' so that the streams of air impinge on each other and cause eddying which in

a round pipe, and in an elbow such as 15, quickly resolves itself into a pulsating and whirling flow. The whirling or spinning of the air is aided in some degree by the rapidly rotating valve 17, which indicates a further advantage in the use of the propeller 18. Thus the air becomes quickly warmed up and is uniformly admixed to the combustible mixture. While all this transpires there is the constant interaction between the suction and the pull of the propeller, as adjustably modified by gravity, so that it is seen that the motor and its fan cooperate with the valve structure and the rotating propeller to avoid waste of fuel and to maintain a highly sensitive interrelation of the parts without requiring any direct actuator connection to the carburetor or the fan. It is noteworthy that the force of gravity is a constant quantity, and because the valve unit is inclined, that effect is small. But it is important for moving the valve to close the ports progressively and bring the valve into immediate and strong responsive relation to the suction when the motor is slowed down.

Having described my invention, I claim:

1. A device constructed for connection to the intake manifold of an internal combustion engine in confronting relation to the cooling fan thereof, which device comprises a casing, a piston valve slidable and rotatable therein, the casing having means for connection thereof to the intake manifold and having openings communicating with the intake manifold and with the atmosphere, said openings being controlled by the slidable valve and being of such size as to be adapted to admit a regulated supply of air into the manifold to rectify the proportions of fuel and air as the engine speed increases, and a propeller-like element exposed to the atmosphere and adapted to be responsive to the blast of air from the engine fan to cause rotation of the propeller and to produce a force axial thereof tending to open the valve, the latter being axially directly fixedly connected to the propeller so as to be caused to spin while the valve and propeller move axially as a unit in opening and closing the valve, and said means being adapted to mount the casing at an acute angle to the horizontal to cause the valve and propeller unit to gravitationally slide to a position in which the valve closes said openings, said valve being so related to the casing and said openings as to be responsive to the manifold suction tending to close the valve, in opposition to the axial force of the propeller.

2. A device responsive to the suction at the intake manifold of an internal combustion engine and to the blast of air from the cooling fan of the engine to change the proportions of the combustible mixture upon an increase in the speed of the engine, including an intake manifold for the engine, a casing, an angular member connecting an end of the casing with the manifold, so that the axis of the casing extends at an acute angle to a horizontal plane, an elongated valve in

the casing slideable along the axis of the casing and rotatable about said axis, a propeller rotatably slidably mounted on the casing and being axially connected to the valve so that the latter is caused to rotate and the valve and propeller are slidable as a unit, said casing having openings communicating with the manifold and with the atmosphere for admitting a quantity of air to the engine sufficient to reduce the richness of the combustible mixture as the engine increases in speed, said valve being gravitationally urged to a position in which it closes the openings, and said propeller being opposed to the said fan to be rotated thereby and to produce an axial force causing opening movement of the valve, and said valve being so related to the casing that the engine suction tends to close the valve, whereby rotation of the valve and propeller unit renders the same easily slidable in response to the opposing forces of said suction and of the fan blast.

3. A device responsive to the suction at the intake manifold of an internal combustion engine and to the blast of air from the cooling fan of the engine to change the proportions of the combustible mixture upon an increase in the speed of the engine, including an intake manifold for the engine, a casing, a member connecting an end of the casing with the manifold, an elongated valve in the casing slideable along the axis of the casing and rotatable about said axis, a propeller rotatably slidably mounted and being axially connected to the valve so that the latter is caused to rotate and the valve and propeller are slidable as a unit, said casing having openings communicating with the manifold and with the atmosphere for admitting a quantity of air to the engine sufficient to reduce the richness of the combustible mixture as the engine increases in speed, and said propeller being opposed to the said fan to be rotated thereby and to produce an axial force causing opening movement of the valve, and said valve being so related to the casing that the engine suction tends to close the valve, whereby rotation of the valve and propeller unit renders the same easily slidable in response to the opposing forces of said suction and of the fan blast.

4. A device responsive to the suction in the intake manifold of an internal combustion engine and to the air stream caused by the cooling fan of the engine to control the supply of auxiliary air to the manifold including a casing having means for connecting the same to the intake manifold, said casing having atmosphere air inlets, a rotatable piston valve in the casing controlling said inlets, and a propeller axially connected to said valve, said propeller being external of the casing and being adapted to be actuated by the air stream so that the valve and propeller are rotatable and axially movable as a unit by the air stream.

RAYMOND DE FILIPPIS.
